UNITED STATES PATENT OFFICE.

GEORGE A. TRUE, OF DETROIT, MICHIGAN, ASSIGNOR OF ONE-HALF TO NORTHERN ENGINEERING WORKS, OF DETROIT, MICHIGAN, A CORPORATION OF MICHIGAN.

MONORAIL-TROLLEY-TRUCK CONSTRUCTION.

1,035,922.

Specification of Letters Patent. Patented Aug. 20, 1912.

Application filed January 19, 1912. Serial No. 672,205.

To all whom it may concern:

Be it known that I, GEORGE A. TRUE, a citizen of the United States of America, residing at Detroit, in the county of Wayne and State of Michigan, have invented certain new and useful Improvements in Monorail-Trolley-Truck Construction, of which the following is a specification, reference being had therein to the accompanying drawings.

The invention relates to mono-rail trolley constructions and the invention consists in various features of construction as hereinafter set forth.

15 In the drawings,—Figure 1 is a perspective view of one of the trolleys and a portion of the truck frame; Fig. 2 is a cross section thereof.

In the construction of overhead trolleys 20 it is usual to arrange wheels upon opposite sides of the L-beam or other track member which are engaged by a bifurcated frame or hanger for supporting the carriage. In case of the breaking of either of 25 these wheels or its axle there is nothing to prevent the disengagement of the hanger and dropping of the load. Thus it sometimes happens that the pounding of the wheels in bridging gaps between adjacent rails or in 30 crossing any other irregularity in the track will result in the crystallization of the metal and eventually in the breaking of the wheel or axle with disastrous results. Another accident that sometimes occurs is 35 the disconnection and dropping of the carriage from the hanger due to the disengagement of the king bolt which forms the pivotal connection therebetween.

It is the object of the invention to 40 overcome these difficulties which is accomplished first, by the peculiar construction of the hanger which is provided with guards for engaging with the rail to prevent dropping of the load where the wheel or axle is 45 broken; second, in the peculiar construction of means for securing the king bolt to prevent accidental disengagement of the carriage from the hanger.

In detail A is a section of an overhead 50 trolley track, B is a bifurcated hanger or track frame on which are mounted the track wheels C for engaging the opposite flanges D and D' of the track, E is the carriage frame which is suspended by the hanger 55 through the medium of a king bolt F en-

gaging a block or member G arranged between parallel beams H and H' of the carriage frame.

To guard against accidental disengagement of the hanger, the bifurcated frame B 60 is provided with extensions I on opposite sides and on opposite ends thereof, which extensions pass around the wheels and inward into proximity to the web of the track beam. The lower flanges J of these extensions are separated but a slight distance from the flanges D and D' of the track so that the failure of any one of the wheels or its axle 65 will result merely in the slight dropping of the frame to rest the flange J upon the track. 70

To guard against disengagement of the carriage frame from the hanger I have provided a strap member K which is bolted or otherwise secured to the opposite sides of the hanger B and passes downward and beneath the block G. The lower portion of the strap has a recess L therein adapted to receive the head of the king bolt and preventing the same from turning. Thus the unscrewing of the nut from the king bolt is 75 prevented and in case of the breaking of the bolt the load would still be sustained by the engagement of the strap with the block G.

What I claim as my invention is: 85

1. In an overhead trolley truck, the combination with a bifurcated truck frame or hanger for embracing the truck beam, of truck wheels journaled upon said frame and engaging the track, and a guard projecting 90 inward from said frame and overhanging the track, said guard being adapted to sustain the load upon failure of the wheel and being arranged in immediate proximity to the track so that upon failure of the wheel 95 but a slight dropping of the frame will be permitted.

2. In an overhead trolley truck construction, the combination of a bifurcated trolley frame or hanger, pairs of wheels on opposite sides of said frame for engaging the opposite flanges of the track, and lateral extensions of said frame passing around said wheels and inward toward the web of the track beam with their lower edges in 100 proximity to the track.

3. The combination with an overhead trolley truck, of a carriage frame suspended therefrom, a king bolt for attaching said frame to said truck, and a guard embracing 105

the king bolt for sustaining the load upon failure or disengagement of said king bolt.

4. The combination with an overhead trolley truck, of a carriage frame suspended therefrom, a king bolt for attaching said frame to said truck, a block or cross member on said carriage frame with which said king bolt is engaged, and a strap embracing said trolley truck passing beneath said block 10 and adapted to sustain the load.

5. The combination with an overhead trolley truck, of a carriage frame suspended therefrom, a king bolt for connecting said truck to said frame, a block or cross member on said frame with which said king bolt 15 is engaged and below which the lower head of the king bolt is arranged, and a strap

embracing said truck passing beneath said block and having a recess for receiving the head of said bolt to prevent turning thereof. 20

6. The combination with an overhead trolley truck, of a carriage frame suspended therefrom, a king bolt for attaching said frame to said truck, a block or cross member on said carriage frame with which said 25 king bolt is engaged, and means associated with said block for sustaining the load upon failure or disengagement of said king bolt.

In testimony whereof I affix my signature in presence of two witnesses.

GEORGE A. TRUE.
